DISPLAY CABINET

Thomas J. Pilliod and Ferdinand C. H. Müller,
Swanton, Ohio, assignors to The Pilliod Cabinet Company, Swanton, Ohio, a corporation of Ohio

Application April 8, 1937, Serial No. 135,754

6 Claims. (Cl. 217—63)

This invention relates to cabinets for the holding and displaying of articles, such for instance as silverware.

The object of the invention is the provision of a cabinet of this character having a novel roll-top type of cover which is preferably transparent to permit effective display of the cabinet contents, and is easily movable to open position to render the contents accessible.

Another object of the invention is the provision in a cabinet of this class of a novel and efficient means for assembling and guiding the separate sliding cover members in the cabinet.

Further objects and advantages of the invention will be apparent from the following detailed description, and from the accompanying drawing, in which—

Figure 1 is a perspective view of a cabinet embodying the invention, with the cover members in closed position; Fig. 2 is an enlarged longitudinal vertical section taken on the line 2—2 in Fig. 1; Fig. 3 is an enlarged fragmentary section taken on the line 3—3 in Fig. 2; Fig. 4 is an enlarged fragmentary section on the line 4—4 in Fig. 1, and Fig. 5 is an enlarged perspective sectional detail of the bottom end portion of a cover member, together with a portion of an engaged wall.

Referring to the drawing, 1, 1 designate the two opposed side walls of the case which are rigidly connected at their ends, preferably near their top edges, by respective cross-bars 2, and intermediate said bars in spaced relation thereto by a bottom member 3. The member 3 is disposed below the plane of the bars 2, so as to cooperate therewith to effectively brace the side members against collapsing and is spaced above the bottom edges of the side members 1, 1 to permit movement of the cover members under the bottom member, as hereinafter described. In the present instance, the bottom member 3 is shown as having a slotted bar or comb 4 on its top for mounting silverware.

The bottom 3 is covered and enclosed at its ends, in the present instance by a pair of oppositely sliding cover members 5, 5, the side edges of which are mounted for sliding movements, in the manner of roll-type covers, in respective grooves 6 provided in the inner sides of the side walls 1, 1. Both covers, for simplicity of assembling, are mounted at each edge in a single groove 6 which extends over the bottom 3 lengthwise of the respective side 1 near its top edge, and at the end of such member extends downwardly and inwardly in curved form around the ends of the

bottom, at the inner sides of the bars 2, with its ends extending in parallel lapped relation under the bottom and past the center line of its length. The lower one of the lapped ends curves down to and opens without the bottom edge of the side 3 member, as shown at 7 in Fig. 2.

In assembling, both covers 5 are threaded into the guide grooves through the open ends 7 thereof and are then moved around to the position shown in Figs. 1 and 2. A screw 8 may then be inserted in each groove near its open end to serve as a stop for limiting the open movements of the adjacent cover. A stop 9 may also be inserted in the central top portion of each groove to limit the closing movements of the covers.

Each cover 5 comprises a single sheet of fairly stiff resilient material, which is preferably, but not necessarily, transparent to permit the contents of the case to be viewed therethrough. This material has the appearance of celluloid, and is preferably of a non-inflammable cellulosic nature. Each sheet 5 at its top end is attached to a cross-bar 10 which is lengthwise slotted to receive the sheet edge. Pins 11 anchor the sheet edge in the bar. Each end of the bar 10 has a guide pin 12 projecting centrally therefrom and engaging within the respective groove 6 (Fig. 3). The opposite end of each cover 5 is stiffened by a crossbar 14 preferably of angle form. One flange of the bar has its ends extended to enter the grooves 6 for movements therein. The bar, in its present embodiment, is composed of sheet metal bent in angle form with the metal at the outer edges of the flanges extended and bent back upon the outer side of the respective flange to render it of double thickness. The adjacent edge of the cover sheet is attached to the bar by being clamped between one of said flanges and its turned-back portion, as shown in Fig. 5.

It is found in practice that the ease of movement of the edges of the cover sheets in the grooves 6 is facilitated by crimping the sheet edges at spaced intervals, as shown at 15, and imparting a slight, normally retained, bow to the sheet material intermediate the crimps, as shown at 16 (Fig. 4). This causes each edge section or panel of the sheet to have a three-point bearing in the groove, as indicated. This feature, in addition to facilitating movement of the sheet edges in the grooves, tends to prevent looseness and rattling of the cover sheets in the grooves and also to prevent buckling of the sheets when being opened by pressure applied to their top ends. In the present instance, the crimps and bows are extended entirely across the cover sheets, as this

is found to present a very attractive appearance to the covers and cabinet as a whole.

We wish it understood that our invention is not limited to any specific construction, arrangement or form of the parts, as it is capable of numerous modifications and changes without departing from the spirit of the claims.

Having thus described our invention, what we claim as new, and desire to secure by United States Letters Patent, is:

- 10 1. A cabinet having cover guiding grooves in opposed walls, and a cover of resilient sheet material of cellulosic nature, having its opposed side edges mounted for sliding movements in said grooves, said edges each having successive crimps spaced lengthwise thereof with each crimp of less height than the thickness of the groove in which it travels, the sheet material between each succeeding pair of crimps being bowed to have 20 central yielding bearing contact at its convex side with one wall of the groove and to cause the crimp portions at the ends of the bow to have yielding bearing contact with the opposite wall of the groove, the bowed portions being free to 25 expand lengthwise of the cover when compressed.
- 15 2. A cabinet having cover guiding grooves in opposite walls, and a cover of resilient sheet material of cellulosic nature, guided at its edges for sliding movements in said grooves, and having a 30 stiffening bar at each end, one of said bars having a slot therein in which the respective end edge of the sheet is anchored and having guide pins projecting from its ends into the grooves.
- 25 3. A cabinet having cover guiding grooves in 35 opposite walls, and a cover of resilient sheet material of cellulosic nature, guided at its edges for sliding movements in said grooves and having a stiffening bar at each end, one of said bars being of angle form in cross-section and constructed 40 of sheet metal with the metal at the outer edge of at least one flange doubled back upon the flange and clamping the adjacent edge of the cover sheet thereto, one flange of said angle bar being projected at its ends into the grooves.
- 45 4. A cabinet having opposed side members, and a bottom member rigidly connecting the side

members above their lower edges and terminating short of the ends of the side members, said side members each having a single guide groove in its inner face extending lengthwise of the side member adjacent to its upper edge, thence 5 curving downwardly and inwardly around and under the respective ends of the bottom member and lapping beneath said bottom member, one end of the groove opening without the bottom edge of the respective side member, two cover 10 members of flexible sheet material threaded at their edges into grooves through the open ends thereof and being oppositely movable to opened and closed positions, and removable stop means in the open end portion of at least one of said 15 grooves.

5. A cabinet having curved cover guiding grooves in opposed walls, a sheet-like cover of cellulosic nature having its opposed side edges mounted for sliding movements in said grooves, 20 said edges each having successive portions forming lengthwise extending bows with their respective end edges bearing against one wall of the associated groove and with their intermediate portions in central bearing contact with 25 the opposite wall, said bows each having a springing tendency to increase the depth of the bow more than the depth of the groove, whereby to yieldingly engage opposed walls of the groove.

6. A cabinet having curved cover guiding 30 grooves in opposed walls, a sheet-like cover of cellulosic nature having its opposed side edges mounted for sliding movements in said grooves, said cover having crosswise extending stiffening crimps and a bowed portion between each pair 35 of crimps, said crimps at each end bearing against one wall of a respective groove and each bowed portion bearing at its convex side against the opposite wall of the groove, said bowed portions being maintained slightly compressed from 40 normal by the groove walls, whereby said crimps and bowed portions have opposed yielding engagement with such walls.
